HAMILTON NEIL WYLIE, OF EDINBURGH, SCOTLAND, ASSIGNOR TO ARMSTRONG SIDDELEY MOTORS LIMITED, OF PARKSIDE, COVENTRY, ENGLAND.

METAL SPAR FOR AIRCRAFT.

1,407,242.

Specification of Letters Patent. Patented Feb. 21, 1922.

Application filed August 22, 1919. Serial No. 319,245.

To all whom it may concern:

Be it known that I, HAMILTON NEIL WYLIE, major in the Royal Air Force, a subject of the King of Great Britain, residing at 19 5 Comiston Drive, Edinburgh, Scotland, have invented certain new and useful Improvements in Metal Spars for Aircraft, of which the following is a specification.

This invention relates to aeroplane spars 10 and other members which are formed of thin metal, and more particularly to such members which are of girder form consisting of two oppositely disposed booms connected by webs. 15 The invention consists essentially in adapting the thin metal, both of the booms and of the webs, to withstand longitudinal compression and shear stresses by curving it about longitudinal axes, so that its cross section is 20 a series of sinuous curves. Each bay of the sinuous curve is curved to a sufficient degree to enable the metal to develop the necessary stresses.

In the accompanying drawings Figs. 1, 2, 25 3, 4 and 5 show in cross section examples of metal aeroplane spars constructed according to my invention, and Fig. 6 shows a detailed construction.

A preferred form of cross section is shown 30 in Fig. 1 where the booms A consist of corrugated metallic strips of which the curvature of corrugation is not such as will cause the strip to fracture while being formed; and is still such as will enable the booms to 35 develop high compression stress without local buckling. It has been found that for a compression stress of 100 tons per square inch in steel members, the radius of curvature must not exceed 60 times the thickness 40 of the metal in a perfectly formed section, while in a section that is dented or irregular a smaller radius is necessary. For ordinary work a radius of curvature not exceeding 30 times the thickness is generally preferred. 45 The fittings necessary for transmitting loads to the spar will be adapted to distribute the loads properly over the webs and flanges, and to maintain the webs in their proper form where the loads are applied but 50 such fittings do not form part of my present invention.

The edges of the web B and the booms A are flanged so as to lie together and be connected by riveting, by electric welding or 55 other suitable means. The extreme edges

of the web are rolled to a relatively small radius so as to form channels C, which receive the edges of the boom and hold them in position during assembly. This formation of the small radius also stiffens the projecting 60 flanges F, F', and prevents them from failing by crinkling under compressing stress.

The sheets forming the web B are also formed into longitudinal corrugations to enable them to withstand compression and 65 shear. These corrugations have preferably a sharper curvature near to the booms where the compression stress may be greater than near to the centre. The central corrugations in the two sheets forming the web bring 70 them into contact along the centre line X and they are directly connected together by riveting. This connection greatly stiffens the section against change of form.

The spar illustrated in Figure 2 is similar 75 to that described in connection with Figure 1, except that the booms A have additional corrugations G and that the edges of the booms are rolled so as to embrace the flanged edges of the webs as at F. Each of the sheets 80 forming the web B, moreover, comprises two strips and all four web strips are connected along the centre line X, by riveting or other means.

The spar illustrated in Figure 3, is similar 85 to that described in connection with Figure 1, except that the sheets forming the web B do not come together.

The spar illustrated in Figure 4, is similar 90 to that described in connection with Figure 2, except that the tubular portions are spaced apart and connected by an additional web D. This web is made sufficiently wide to bear against the booms A as at H, and thus facilitates assembly.

The spar illustrated in Figure 4 is similar 95 to that described in connection with Figure 5, except that each part A, and adjacent parts B, are made from a single strip. This eliminates the flanges F, F', shown in Figure 100 1, with the result that the lines of connection of the booms to the web D are relatively close to the centre of the spar and are therefore relatively lightly stressed by forces tending to bend the spar.

Given a sufficiently hard steel, a compression stress of 100 tons per square inch can be developed in this section provided the circumference of each flange does not substantially exceed 200 times the thickness of the 110

metal and that the radius of curvature of no outer part exceeds about thirty times the thickness of the metal.

In Figure 6 the flanged edge F' of the web 5 B is shown extended and bent over so as to embrace the curved edge F of the boom A.

When extreme lightness is necessary the members hereinbefore described may have less thickness than follows from the ratios 10 given above as necessary to develop 100 tons per square inch in hard steel.

When the members are thus made in extremely thin metal, the extreme thinness may cause failure to occur before the metal is 15 stressed to its elastic limit. The strength of such thin members when other things are equal has been found to be substantially proportional to the elastic constant of the metal used.

20 The longitudinal corrugations of the webs as well as the flanges of the member is important as it enables the metal to be reduced to one quarter of the least thickness which it would otherwise require to have to withstand 25 a given shear stress.

The forms of members described herein are suitable for other than aircraft structures.

What I claim as my invention and desire 30 to secure by Letters Patent is:—

1. A metal girder comprising in combination two oppositely disposed booms of thin metal bent about longitudinal axes into sinuous curves, and a thin metal web connecting said booms and bent about longitudinal axes into sinuous curves.

2. A metal girder comprising in combination two oppositely disposed booms of thin metal bent about longitudinal axes into 40 sinuous curves, and a thin metal web connecting said booms composed of a plurality of separate sheets bent about longitudinal axes into sinuous curves.

3. A metal girder comprising in combination two oppositely disposed booms of thin metal bent about longitudinal axes into 45

sinuous curves, and a thin metal web connecting said booms composed of a plurality of separate sheets bent about longitudinal axes into sinuous curves, the edges of said web and the edges of said booms being of similar curvature adapted for seating one against the other. 50

4. A metal girder comprising in combination two oppositely disposed booms of thin metal bent about longitudinal axes into sinuous curves, and a thin metal web composed of a plurality of separate sheets bent about longitudinal axes into sinuous curves, the edges of the web being extended and 55 bent over so as to embrace the curved edges 60 of the booms.

5. A metal girder comprising in combination two oppositely disposed booms of thin metal bent about longitudinal axes into 65 sinuous curves, a thin metal web connecting said booms composed of two separate sheets bent about longitudinal axes into sinuous curves, the curves of one sheet in opposed relation to the curves of the second sheet, 70 the central curve of the one sheet contacting with and secured to the central curve of the other sheet, the edges of the said sheets forming the web being secured to the edges of the upper and lower booms. 75

6. A metal girder comprising in combination two oppositely disposed booms of thin metal bent about longitudinal axes into sinuous curves, a thin metal web composed of a plurality of separate sheets bent about longitudinal axes into sinuous curves the curves near the booms being sharper than the curves in the central portion of the web, the edges of the said sheets forming the web being secured to the edges of the upper and 80 lower booms.

In witness whereof I have hereunto set my hand in the presence of two witnesses.

HAMILTON NEIL WYLLIE.
